ANDREW F. BAUM, OF NEW YORK, N. Y., ASSIGNOR TO L. H. ROCKWELL.

Letters Patent No. 78,414, dated June 2, 1868; antedated May 22, 1868.

IMPROVEMENT IN CATAMENIAL SACKS.

The Schedule referred to in these Letters Patent and making part of the same.

TO ALL WHOM IT MAY CONCERN:

Be it known that I, ANDREW F. BAUM, of the city, county, and State of New York, have invented a new and useful Improvement in Catamenial Sack; and I do hereby declare that the following is a full, clear, and exact description thereof, which will enable others skilled in the art to make and use the same, reference being had to the accompanying drawings, forming part of this specification, in which—

Figure 1 is a view of the open side of the India-rubber catamenial sack, showing my improved rolled edge. Figure 2 is a transverse section, taken in the line xx , fig. 1.

Similar letters of reference indicate corresponding parts.

This invention relates to an improvement in India-rubber catamenial sacks, and consists in forming the edges by rolling up the material into a solid bead or rib, and then curing it with soluble rubber, to make a strong and elastic binding.

I am aware that India-rubber catamenial sacks are made with inflated cushions or bolsters to form the edges, and also with flaps or folds of the material, to double the thickness of the edges, but both of these plans are defective, on account of want of strength and durability.

The gum becomes heated by contact with the person, and the double edges of the flat sack are thus weakened, and give way easily, while the same cause immediately destroys the inflated cushions by the expansion of the air within, which bursts and escapes, thus in both cases rendering the sacks unserviceable, and exposing the wearer to unpleasant accidents.

My improved rolled-edge sack is designed to overcome these difficulties, by an increase of strength in a very compact, neat, and convenient form. The rolled edge, although solid and strong, is elastic, and adapts itself to the conformation of the person, making it an agreeable appendage to wear.

The preparation and management of the material for forming the sack are the same as those ordinarily pursued in the manufacture of India-rubber sacks, two pieces of sheet rubber being cut and joined together longitudinally by the gum in solution, to form the oval cup, and then cured.

When the sheet rubber is cut to form the sack A, I extend the sides to form my rolled edges far enough to roll up and make the edges $a a$ on both sides of the sack, as shown in fig. 1. This extension of the sides, for the purpose of forming the rolled edges $a a$, is also indicated in red in fig. 1, and the manner of rolling up the sheet rubber to form the edges $a a$ is shown in fig. 2.

The edges thus formed are saturated with the rubber in solution, as commonly prepared for uniting two pieces in the manufacture of articles of this material, at the time the middle seam of the sack is joined, and I also then attach by the same means two straps, $b b$, for securing the sack to the person of the wearer in the usual way. But it will be observed that the straps are shaped broad, and oval at their junction with the sack, which improved form fits the person better, and prevents the strap from working by wear into a mere string, like the ordinary straight strap.

Having thus described my invention, what I claim as new, and desire to secure by Letters Patent, is—

An India-rubber catamenial sack, formed with rolled edges $a a$, substantially as described.

The above specification of my invention signed by me, this 12th day of February, 1867.
